Inventor:

UNITED STATES PATENT OFFICE.

OTTO HOFFMANN, OF BERLIN, GERMANY.

TROLLEY-HEAD.

No 841,397.

Specification of Letters Patent.

Patented Jan. 15, 1907.

Application filed August 22, 1905. Serial No. 275,213.

To all whom it may concern:

Be it known that I, OTTO HOFFMANN, technical manager, a subject of the King of Prussia, German Emperor, residing at Grosse 5 Frankfurterstrasse 10, Berlin, O., in the Province of Brandenburg, Kingdom of Prussia, and Empire of Germany, have invented new and useful Improvements in Trolley-Heads, of which the following is a 10 specification.

This invention has for its object a current-taker or trolley for electric railways and the like, having two rollers simultaneously in contact with the overhead wire, in which any 15 slipping off or springing off is prevented by a spring-yoke inclosing the conducting-wire after the manner of a clamp, being and arranged round the ordinary trolley-roller and pivoted on the axis of the roller. The free 20 aperture of this yoke for the reception of the wire has the same or approximately the same section as the wire, and is held in the correct position relative to the wire by means of an auxiliary roller mounted thereon.

25 In order to more particularly describe the invention, reference is made to the accompanying drawings, in which—

Figure 1 is a side view of the current-taker or trolley with a low-lying overhead wire; 30 Fig. 2, a side view with a higher overhead wire. Fig. 3 shows the connection of the fork with the frame formed of side bars. Fig. 4 is a top view of the current-taker when traveling round a particularly sharp curve of the conductor, and, finally, Fig. 5 is a view of the 35 current-taker seen from below.

The two side parts *a* of the clamp-like yoke are connected by a screw *d* and releasably and revolvably mounted by means of 40 slots between the main roller *b* and the fork *c* on the axle *k* of the main roller *b*, while two springs *h*, arranged in lugs *g* and acting on set-pins *e*, produce the spring action of the yoke, which is held in a suitable position relative to the conducting-wire by a guide-roller 45 *f*, mounted between the side bars. The clamp-like yoke thus formed by the two side bars *a* may, as shown more particularly in Fig. 3, when the rear part has been turned 50 upward be pushed down between the main roller *b* and fork *c* up to the bushes *i* of the main roller-axle *k*. If then the yoke be turned down to the right, the projections *l* come into action and are guided by means of 55 the two lower edges *m* of the fork *c* in a course concentric to the main roller *b*, and

thereby secure a firm attachment of the clamp-like yoke on the fork *c*. After the insertion of the yoke the two springs *h* are attached to the hooks *n* on the forked projection *o*. In this way the yoke is connected elastically and pivotally with the fork. These arrangements for the easy removal of the yoke are employed in order to allow it to be easily cleaned and oiled and any yokes 65 which have become defective by use to be easily replaced by fresh ones without long interruption of the working.

When in use with overhead wires of known form, the two outer sides of the clamp-like 70 yoke formed by the side bars *a* allow of the trolley being carried through safety devices—for instance, guide-bars or the like—mounted on the upper wire for preventing the ordinary trolley, only consisting of roller and fork, 75 from slipping off at curves and crossings. For this object the yoke must have about the same width as the contact-roller of the ordinary current-taker hitherto utilized for existing overhead wires.

Shoulders or jaws *p*, Fig. 4, between which 80 a free space is left, the clear width of which space is exactly as large or only slightly larger than the diameter of the traveling wire, are provided on the side bars *a*, so that the 85 wire is absolutely held fast on a curve, as in a clamp, because in this case the free space or section is smaller than the corresponding oblique section of the wire. The shoulders *p* form, together with the recessed main roller 90 *b*, an open space of oval form round the conducting-wire, through which space the wire slides, during working being almost completely secured against springing out on straight as well as curved stretches. It can, 95 in fact, only spring out if it should happen that the wire should coincide mathematically exactly with the opening between the jaws. When the roller is to be placed against the wire, the edges of the shoulders *p* 100 must be parallel with the axis of the wire. In order to facilitate the entrance of the conductor-wire through the opening, bevelings are formed on the upper parts of the side jaws, while by means of a spring member 105 *t*, formed on the fork-shaft, permitting lateral movement, the trolley may be placed against the wire when the overhead wire is in a position inclined to the roller.

The side jaws are beveled off to the front 110 and the rear in order, on the one hand, to allow of the suspension-lugs *q*, which connect the

working wire *r* and the support-wires *s*, even in the case of very rapid traveling, to slip easily through the longitudinal opening, and, on the other hand, to facilitate secure traveling round curves. The side jaws may also be held apart by the yoke and be provided with a linked strongly inward springing device parallel to the axis of the working wire in order to allow any intermediate pieces of larger section existing in the wire to also pass through.

The guide-roller *f* and the two springs *h* have for their common object to maintain the clamp-like yoke, above described, always in the same relative position to the overhead wire, whether the wire be placed high or low.

The springs on the vehicle which press the trolley-pole with the current-taker against the wire must be so powerful that the power of the springs *h*, arranged on the side bars *a*, is easily overcome and a constant and uniform contact of both rollers of the current-taker with the overhead wire is obtained.

Having now particularly described and ascertained the nature of my said invention and in what manner the same is to be performed, I declare that what I claim is—

1. In a device of the character described, the combination of a trolley-head, a yoke formed with a plurality of members, each of said members having a slot formed therein adapted to fit the axle of the trolley-wheel and spring-operated means for maintaining said slots in position on said axle.

2. In a device of the character described, the combination of a forked member, a current-taking wheel mounted therein, a yoke formed of a plurality of members and provided with slots adapted to fit the axle of

said current-taking wheel, spring-operated means for holding said slots in position on said axle, and means for limiting the movement of said yoke.

3. In a trolley-head, the combination of a forked member pivotally mounted on a suitable pole, a trolley-wheel mounted in said forked member, a clamp-like yoke provided with slots adapted to fit upon the axle of said trolley-wheel, an auxiliary wheel mounted in said yoke, springs connected to said yoke and said forked member and lugs on said yoke adapted to engage said forked member.

4. In a trolley-head, the combination of a forked member pivotally mounted on a suitable pole, a trolley-wheel mounted on said forked member, a yoke comprising two members, each member being provided with a downwardly-open slot adapted to fit upon the axle of said trolley-wheel, an auxiliary wheel mounted in said yoke, projections on said forked member, springs detachably secured to said projections and to said yoke and lugs on said yoke adapted to engage said forked member.

5. In a device of the character described, the combination of a forked member pivotally mounted on a suitable support, a trolley-wheel mounted therein, a yoke provided with slots adapted to rest upon and partly surround the axle of said trolley-wheel, springs for maintaining said slots in position on said axle, and means for limiting the movement of said yoke.

OTTO HOFFMANN.
